CLAIM

The ornamental design for a display screen or portion thereof with graphical user interface for display of bird's eye view, as shown and described.

DESCRIPTION

The sole FIGURE is a front view of a display screen or portion thereof with graphical user interface for display of bird's eye view showing our new design.

The dotted line shown as part of an icon and the heavy weight dashed lines are claimed elements of the design. The broken line showing of the display screen or portion thereof and the remainder of the graphical user interface forms no part of the claimed design.
